CLAIM

The ornamental design for a Valve Handle for a Container as shown and described.

DESCRIPTION

FIG. 1 is a top perspective view of the “Valve Handle for a Container”, showing my new design;

FIG. 2 is a bottom perspective view thereof;

FIG. 3 is a top plan view thereof;

FIG. 4 is a right side elevational view thereof;

FIG. 5 is a front elevation thereof;

FIG. 6 is a back elevation view thereof;

FIG. 7 is a right side elevation view thereof;

FIG. 8 is a left side elevation view thereof; and

FIG. 9 is a cross-sectional elevation view thereof, taken at section line 9-9 in FIG. 3.

The broken lines are shown for the purpose of illustrating parts of the article that form no part of the claimed design.

1 Claim, 6 Drawing Sheets(56)
